UNITED STATES PATENT OFFICE.

MORRIS W. JACOBI, OF WEEHAWKEN HEIGHTS, NEW JERSEY.

DOOR FOR BAKERS' OVENS.

1,086,918.

Specification of Letters Patent. Patented Feb. 10, 1914.

Application filed March 10, 1913. Serial No. 753,466.

To all whom it may concern:

Be it known that I, MORRIS W. JACOBI, a citizen of the United States, residing at Weehawken Heights, county of Hudson, 5 and State of New Jersey, have invented a new and Improved Door for Bakers' Ovens, of which the following is a specification.

This invention relates to a baker's oven door of novel construction which can be 10 readily fitted in position, and which permits an escape of the steam from the baking chamber into the chimney while the door is open, and an escape of steam from the bakery into the chimney when the door is closed, 15 so that the atmosphere and temperature of the bakery is correspondingly improved.

In the accompanying drawings: Figure 1 is a front view of a door for bakers' ovens embodying my invention; Fig. 2 a cross 20 section on line 2—2, Fig. 1; Fig. 3 a cross section on line 3—3, Fig. 1; Fig. 4 a longitudinal section partly broken away on line 4—4, Fig. 3; Fig. 5 a perspective view of 25 part of one of the side plates and of the operating block, and Fig. 6 a section on line 6—6, Fig. 3.

The frame of the oven door is of such a size and form as to snugly fit into the mouth 10 of the baking chamber 11. It is composed of a top plate 12 having depending rear flange 13, and front flange 14, a pair of side plates 15, and a bottom plate 16 having depending flange 17, said bottom plate abutting with its rear edge against the front 35 edge of the hearth plate 18.

The door proper or leaf 19 is so hung to the side plates 15 as to swing inwardly while being opened, and outwardly while being closed, abutting in its closed position 40 against inclined flanges 20 of the side plates (Fig. 6). Means are provided for readily hanging the door to the frame, and removing it therefrom, so that it can be fitted in position and replaced whenever necessary 45 with very little trouble. To this effect, each side plate 15 is provided near its top with a forwardly opening shallow recess 21 adapted for the accommodation of a block 22, which abuts against front flange 14 of top 50 plate 12. The thinned section 23 of the side plate which forms the wall of the recess is provided with an eye or bearing 24 which opens into a forwardly extending flaring slot 25. Block 22 has a corresponding bearing 26 at its upper edge, and may be removably secured to the wall 23 by a screw

27. Protuberances 28 formed on wall 23 during the casting of the side plate, may be ground down to such an extent, while fitting the parts, that block 22 will obtain a snug 60 seat. The shaft 29 of door 19 may be squared as shown, and is extended laterally some distance beyond the door frame to carry the usual counterweight 30. At those points where the shaft passes through the 65 bearings 24, 26, it is rounded, as shown, to form gudgeons 31 that are freely rotatable within said bearings. In order to hang the door, its gudgeons 31 are passed through slots 25 into bearings 24, blocks 22 are 70 slipped sidewise into the recesses 21 so as to become seated within the same flush with the inner faces of side plates 15, and close up the slots 25, after which the blocks are secured to the walls 23 by the screws 27. In 75 this way the slots 25 are closed up by the blocks 22, so that the gudgeons 31 of the door leaf become confined within the bearings.

The shaft 29 of the door 19 is fitted to the latter some distance below the upper edge 80 thereof, so as to form a top door section 19^a above such shaft. When the door is closed, the upper edge of this section engages the top plate 12, to form a tight joint, section 19^a swinging of course forward while the 85 door is being opened, or swung inward, and backward while the door is being closed or swung outward. Directly back of the front flange 14, there is formed in the top plate 12, a row of openings 32, extending preferably from side to side of the door frame. 90 These openings communicate with the chimney 33 in suitable manner, so that the steam and hot gases passing upwardly through the openings may freely escape. It is preferred 95 however to connect the openings with the chimney by means of the flue 34 of a hood 35 that extends forwardly from the oven directly above the oven frame and which thus constitutes means for carrying off the steam 100 from the oven mouth, as well as from the hood.

The correlation of the parts is such, that when the door 19 is closed (Fig. 3), the openings 32 will be located in front of the 105 top door section 19^a, so that in this position they will assist the hood in carrying off the steam and heat from the bakery. When however the door is opened, its top section 19^a in swinging forward against front flange 14, will cut the openings 32 off the bakery 110 and place them into direct communication

with the back of the oven mouth and thus with the baking chamber 11. In this way, the steam from the chamber 11 will find through the openings a direct exit to the chimney, so that the volume of steam flowing into the bakery is materially diminished and the air of the latter is thus maintained in a pure and cool condition.

I claim:

- 10 1. A baker's oven door comprising a leaf having gudgeons, a door frame having side plates provided with recessed sections, bearings in the recess-walls and slots opening into the bearings, said slots being adapted for the passage of the gudgeons therethrough into the bearings, blocks adapted to be seated within the recessed sections and close up

the slots, thereby confining the gudgeons within the bearings, and means for attaching the blocks to the side plates.

2. A baker's oven door comprising a frame having a front opening, a chimney, means for connecting said opening to the chimney, and a door carried in the frame and having a section adapted to occupy a position at either side of said opening, thereby connecting the opening either with the baking chamber and cutting it off the bakery, or connecting the opening with the bakery and cutting it off the baking chamber.

MORRIS W. JACOBI.
